UNITED STATES PATENT OFFICE.

GEORGE FREDERICK CORBY, OF BRIGHTON, ONTARIO, CANADA.

DESIGN FOR A CRUET.

Application filed June 1, 1925. Serial No. 13,624. Term of patent 7 years.

To all whom it may concern:

Be it known that I, GEORGE FREDERICK CORBY, a subject of the King of Great Britain, and resident of the town of Brighton, county of Northumberland, Province of Ontario, Dominion of Canada, have invented a new, original, and ornamental Design for Cruets, of which the following is a specification, reference being had to the accompanying drawings, forming part thereof.

In the drawings Figure 1 is a side elevation of a cruet, showing my new design.

Figure 2 is a cross sectional view taken on the line A—A of Figure 1.

I claim:

The ornamental design for a cruet, as shown.

GEORGE FREDERICK CORBY.
